UNITED STATES PATENT OFFICE.

AUGUST R. LUSCHKA AND HENDRIK STUKART, OF LAPORTE, INDIANA, ASSIGNEES
TO U. S. SLICING MACHINE COMPANY, OF LAPORTE, INDIANA, A CORPORATION OF
INDIANA.

BREAD-SLICING MACHINE.

Application filed May 16, 1921. Serial No. 469,825.

To all whom it may concern:

Be it known that we, AUGUST R. LUSCHKA and HENDRIK STUKART, citizens of the United States, residing at Laporte, in the 5 county of Laporte and State of Indiana, have invented certain new and useful Improvements in Bread-Slicing Machines, of which the following is a specification.

This invention relates to a machine for 10 slicing bread and similar material, and has for its object the provision of a device of the class named which shall be of improved construction and operation.

The invention is exemplified in the combination and arrangement of parts shown in the accompanying drawings and described in the following specification, and it is more particularly pointed out in the appended claims.

20 In the drawings—

Fig. 1 is an elevation of a bread slicer embodying one form of the present invention;

Fig. 2 is a top plan view of the slicer shown in Fig. 1 with parts in section;

25 Fig. 3 is a rear elevation of the slicer shown in Figs. 1 and 2;

Fig. 4 is a transverse section of the slicer shown in Fig. 1;

Fig. 5 is a front elevation of the slicer 30 shown in Fig. 1;

Fig. 6 is an elevation with parts in section showing a part of the feeding mechanism;

Fig. 7 is a vertical section showing gearing for operating the grinder;

35 Fig. 8 is a vertical section of one form of ratchet drive for the feeding mechanism; and

Fig. 9 is an elevation of one of the parts shown in Fig. 8.

40 As shown in Fig. 1, the slicing machine may be mounted on a suitable support, such as a pedestal 10, upon which the base member 11 of the machine frame rests. At opposite ends of the base 11 are frame plates 45 12 and 13 which are held in spaced relation by the base member 11 and brace rods 14. The rods 14 are connected to a web or plate 15 which is secured to the frame plate 13 by screws 16. The members 13 and 15 are

50 spaced from one another, as shown in Fig. 2, to provide a housing in which is disposed a rotating arm 17 carrying a rotary slicing knife 18. The arm 17, as shown in broken lines in Fig. 4, is in the form of a plate

which constitutes a housing enclosing a pair 55 of gears 19 and 20. The gear 19 is journaled on a stud shaft 21 mounted on the arm or plate 17 and the knife 18 is detachably secured to the gear 19 by screws 22, as shown in Fig. 4. The gear 20 is rigidly fixed to a 60 stud shaft 23 which in turn is rigidly held by a nut 24 to a casing 25. The casing 25 is attached to the frame plate 13 by screws 26, shown in Fig. 5. The arm 17 is formed integrally with a sleeve 27 which is journaled 65 to rotate upon the shaft 23 and which is driven by a sprocket wheel 28 secured to the sleeve 27. The gear 28 is operated by a chain 29 which passes over a sprocket 30 on the end of a drive shaft 31. The drive shaft 70 31 is journaled in bearings 32 and 33 in the end plates 12 and 13, respectively, and is provided with a fly-wheel 34 driven by a belt 35. The belt 35 passes over a pulley 36 on a shaft 37 of a motor 38, the motor being 75 carried from the under side of the base plate 11, as shown in Fig. 1. The fly-wheel 34 may be provided with a detachable handle 39 so that the machine may be operated by hand if desired.

It will be apparent that when the shaft 31 is driven the sleeve 27 will be rotated upon the stud shaft 23 and will carry the arm 17 about the center of the shaft 23 as an axis. This will swing the axis of the knife 18 in 85 an orbit about the shaft 23. At the same time the knife 18 will be driven to rotate upon its own axis by the gears 19 and 20. The gear 20 being stationary will cause the gear 19 which meshes therewith to rotate as 90 it is revolved about the gear 20, thus rotating the knife 18.

The plate 17 is provided with a peripheral flange 40 the edge of which is arranged adjacent the face of the knife 18 thus providing a casing for the gears 19 and 20 and preventing crumbs of bread or other material from contacting with the gears. The upper portion of the housing in which the knife 18 revolves is closed by a door 41 which is 95 hinged by a rod 42 to the upper edge of the web 15 and is held in closed position by a fastening 43. This door will permit access to the knife 18 so that it may be removed for sharpening in a manner to be described or 100 105 for any other purpose.

The loaf of bread or other material to be sliced is supported in a guideway or trough

44 held at its forward end by a flange 45 on the web member 15. The flange 45 surrounds an opening through which the end of the loaf is projected into position to be engaged by the knife 18. A similar flange 46 is formed on the frame plate 13 so that the openings through these flanges register with one another, and the edges of the flanges are spaced apart sufficiently to permit of the passage of the knife 18 therebetween. A slice receiver 47 is pivotally and detachably connected at 48 in position to register with the opening formed by the flange 46 and to receive the slices as they are formed.

15 It will be apparent that the edge of the knife 18 at the time that it is pressed into engagement with the loaf of bread will also be given a movement to produce a drawing cut by the operation of the gears 19 and 20. 20 This enables the knife to cut the loaf without compressing it and it has been found that in this manner even the softest of hot bread can be sliced without difficulty.

In order that the same portion of the edge 25 of the knife 18 will not contact with the loaf at all times the gears 19 and 20 are preferably given a slightly different number of teeth. This arrangement will bring a different portion of the edge of the knife 18 30 into cutting position at each revolution of the arm 17. A gear ratio of "44 to 40" has been found satisfactory for this purpose. This will advance the knife one complete revolution in ten rotations of the arm 17. 35 The bread is fed forwardly after each slice is cut by a clamping device of holder 49 comprising an upright plate 50 against which the end of the loaf is held by curved prongs or tines 51 arranged to be projected 40 through openings 52 in the plate 50. The tines 51 are carried by a pivoted member 53 arranged to swing about a bar 54 carried by brace members 55 projecting rearwardly from the plate 50. The holder 49 is provided 45 with a base 56 which carries upwardly projecting teeth 57 which may be arranged in alignment with the tines 51 when in holding position. The loaf is first placed on the teeth 57 and the member 53 is then swung 50 upwardly and forwardly until the tines 51 pierce the loaf and hold it in the manner shown in Fig. 1.

The holder 49 is carried by a bracket 58 which extends laterally over the edge of the runway 44, as shown in Fig. 4, and is held in place by a lug 59 which engages a bar 60 secured to the upper edge of the side of the runway 44. The bracket 58 is provided with a sleeve 61 through which a feed screw 62 60 extends. A lever 63 is pivoted at 64 upon the upper face of the bracket 58 and is provided with a bolt 65 which may be moved by the lever 63 into and out of engagement with the threads of the feed screw 62. The bracket 65 58 is provided with a continuation 66 which

cooperates with the lever 63 to form a handle by which the bolt 65 may be operated and by which the holder 49 may be moved along the slideway 44 to various positions of adjustment. The lever 63 is preferably provided with a spring normally holding the bolt 65 in engagement with the feed screw 62.

To automatically feed the loaf forwardly during the slicing operation ratchet mechanism is provided for rotating the feed screw 62. This mechanism is driven by a cam 67 secured to the fly-wheel 34 and provided with a cam groove 68 in which a roller 69 travels. The roller 69 is carried at one end of a lever 70 pivotally mounted at 71 on the rear frame plate. A yoke 72 engages the lever 70 and is held in adjusted positions thereon by a set screw 73. A link 74 is pivoted at 75 to the yoke 72 and the lower end of the link is pivotally connected at 76 to a cover plate 77 for a ratchet disc 78. A pawl 79 is connected with the cover plate 77 in position to engage the teeth on the ratchet disc 78. Any other approved one-way drive mechanism may be interposed between the discs 77 and 78 for transmitting the intermittent motion of one to the other. The disc 78 is secured to the rearwardly projecting end of the feed screw 62 and a holding pawl 80 may be pivoted to the frame plate 12 in position to engage a holding ratchet 80 also secured to the feed screw 62. Rotation of the cam 67 will impart a partial rotation to the feed screw 62 at each revolution of the drive shaft 31. The parts are so timed that the movement of the feed screw will take place during the time that the slicing knife 18 is away from the cutting position so that the forward movement of the loaf will take place while the opening for the slices is free from the knife. The amount of rotation of the feed screw 62 and consequently the thickness of the slices may be regulated by adjusting the yoke 72 along the lever arm 70.

In order that the knife 18 may be easily sharpened a spindle 81 is journaled in the frame plate 13 and housing 25, as shown in Fig. 7, and carries a disc 82 on which the knife 18 may be secured by the screws 22 115 in the same way that it is held to the gear 19. Fastened to the spindle 81 is a pinion 83 which may be connected to a gear 84 by means of an idler 85. The idler 85 is carried on a shaft 86 and may be slid into and out 120 of mesh with the gears 83 and 84 by a handle 87 and is held in its adjusted positions by a detent 88 arranged to engage grooves in the handle 87. The gear 84 is fixed on the drive shaft 31. A sharpening device 89 having a 125 grinding wheel 90 is supported on the frame at 91 in position to bring the wheel 90 into cooperative relation with the periphery of the knife 18 when the knife is carried by the spindle 81. The grinder 89 may be of 130

any suitable construction, one form of grinder for such purpose being shown in United States Letters Patent No. 1,308,433, granted July 1, 1919. To sharpen the knife 5 18 it is removed from the spindle 21 and placed on the spindle 81, the idler 85 is brought into mesh with the gears 83 and 84, and the shaft 31 is rotated to drive the knife 18 while in engagement with the grinder 90, 10 as shown in broken lines in Fig. 1. The grinder may be provided with a supplemental stone 92 for engagement with the flat face of the knife to remove the burr, as described in the patent above referred to.

15 It will be seen that with this construction a loaf of any configuration may be held and fed to the slicing knife and that slices of varying thicknesses may be cut from the loaf. The loaf will be sliced to the very 20 end or last slice and the movement of the knife produces a drawing cut so that no difficulty is experienced in slicing all kinds of bread or similar material. The mechanism is arranged so that all portions of the 25 edge of the knife will be used, thus preventing the dulling of any particular portion more than the rest, and provision is made for easily and effectively sharpening the knife as occasion may require. It has been 30 found in practice that a machine of this character will readily slice bread at the rate of two-hundred (200) slices per minute.

We claim:

1. In a slicing machine, a disc knife, 35 means for supporting said knife for rotation about its center and for revolution about an axis removed from said center, and planetary gearing for rotating said knife when revolved about said axis, said gearing 40 having a ratio to change the angular position of said knife about its center each time said knife returns to a given position in its orbit about said axis.

2. In a slicing machine, a disc knife, a 45 plate forming an arm upon which said knife is mounted to rotate, means for revolving said plate about an axis spaced from the center of said knife, gearing for rotating said knife when revolved about said axis, 50 and a flange formed on the periphery of said plate and cooperating with said knife to provide a housing for said gearing.

3. In a slicing machine, a disc knife, means for revolving said knife about an axis 55 removed from the center thereof, a circular casing for enclosing the space in which said knife moves, said casing comprising an integral plate for one side thereof and a divided plate for the other side thereof, one

section of said divided plate being movable 60 to permit access to said knife.

4. In a slicing machine, a disc knife, a spindle upon which said knife is supported, means for revolving said spindle to perform slicing operations, and a stationary spindle 65 arranged to rotate said knife upon a fixed axis to facilitate sharpening of said knife.

5. In a slicing machine, a disc knife, a spindle arranged to engage said knife at the center thereof, means for driving said 70 spindle to rotate said knife, means for revolving said spindle about an axis spaced from the axis of said spindle, a stationary spindle for receiving said knife, means for rotating said stationary spindle about a 75 fixed axis, and a grinder arranged to engage the edge of said knife during its rotation by said stationary spindle to sharpen said knife.

6. In a slicing machine, a disc knife, means for revolving said knife about an axis spaced 80 from the center thereof, a stationary spindle for receiving said knife, means for driving said stationary spindle to rotate said knife about a fixed axis, a grinder for sharpening said knife when driven by said stationary 85 spindle, and means for breaking the driving connection for said stationary spindle during the slicing operation of said knife.

7. In a slicing machine, a disk knife, 90 means for moving said knife bodily to produce a slicing operation, means for rotating said knife about a fixed axis, and a sharpener for engaging said knife during said rotation.

8. In a slicing machine, a disk knife, 95 means for rotating said knife upon its axis and for simultaneously revolving said axis about a point spaced therefrom, and means for retaining the axis of said knife in fixed position and simultaneously rotating said 100 knife thereon for sharpening said knife.

9. In a slicing machine, a casing comprising a fixed front wall, a divided rear wall having the upper portion thereof movable to permit access to the interior of said 105 casing, a disk knife mounted in said casing, and mechanism supported by the fixed portions of said casing for revolving said knife about an axis spaced from the center of said knife, the lower portioins of the walls 110 of said casing having openings therethrough to permit of the passage through said walls of material to be sliced by said knife.

In testimony whereof we have signed our names to this specification on this 9th day 115 of May, A. D. 1921.

AUGUST R. LUSCHKA.
HENDRIK STUKART.
